SELECTIVE VENDING MACHINE

Boley A. Andrews, Kansas City, Kans., and Eugene R. Sabin and Loran A. Shantz, Jr., Kansas City, Mo., assignors to The Vendô Company, Kansas City, Mo., a corporation of Missouri

Application September 29, 1952, Serial No. 312,628

2 Claims. (Cl. 221—152)

This invention relates broadly to vending machines, and has for its primary object to adapt the mechanism of our co-pending application, Serial No. 240,482, filed August 6, 1951, and entitled "Gum Vending Machine," into a multiple unit having a plurality of pairs of stacks of merchandise, each pair preferably being of a different character and each being provided with a manually operable lever, this being a continuation-in-part of said co-pending application.

It is the most important object of this invention to provide a machine for vending gum or the like, which machine includes a plurality of mechanisms for vending such merchandise, each of which is in turn provided with a customer-actuated lever which may be selected after insertion of a coin or like medium, there being structure for permitting actuation of but one lever and therefore, obtaining but one article of merchandise upon insertion of the coin to cover the purchase price.

Another important object of this invention is to provide a vending machine of the aforementioned class, wherein is provided novel interlock assemblies associated with the manually operable levers so as to prevent manipulation of more than one lever at a time, together with a coin-free mechanism coupled with the operating levers in a manner to prevent vending of the merchandise until the coin has been inserted and accepted.

A further object hereof is to provide a spring-type clutch for each operating handle respectively, capable of yielding to pressure applied thereto not only when the coin control apparatus is in the normally locked condition, but while any one handle is depressed.

Another object hereof is to provide a coin controlled plural mechanism vending machine wherein the actuating elements are depressible downwardly toward the supporting surface of the machine to the end that the latter will not be displaced from its support during manipulation by the customer.

Other objects include the way in which the individual mechanisms are rendered inoperable when the stacks of merchandise become depleted; the way in which captive link interlock means is provided in association with the aforesaid structure; the manner of controlling a shaft common to the mechanisms through connection with a single coin control apparatus; and the way in which the shaft is coupled with the series of assemblies for free rotation with respect thereto when any one operating handle is depressed.

In the drawings:

Figure 1 is a front elevational view of a selective vending machine made according to the present invention, a portion of the cover thereof being broken away to reveal details of construction.

Fig. 2 is a vertical, cross-sectional view taken on line II—II of Fig. 1.

Fig. 3 is an enlarged, fragmentary, detailed, cross-sectional view parallel with the sectional view of Fig. 2, illustrating the normal position of one of the operating handles and its associated parts.

2

Fig. 4 is a cross-sectional view similar to Fig. 3, illustrating the position of one of the operating handles and its associated parts when the handle is depressed to the limit of its travel if no coin is inserted in the machine, and assuming that the spring clutch thereof is not energized.

Fig. 5 is a cross-sectional view similar to Figs. 3 and 4, illustrating the position of one handle and its associated parts when the handle is released following acceptance of a coin and prior to delivery of an article of merchandise.

Fig. 6 is a cross-sectional view similar to Figs. 3, 4 and 5, illustrating the position of one of the operating handles and its associated parts when the handle is swung to the lowermost end of its path of travel for causing vending of an article of merchandise.

Fig. 7 is an enlarged, fragmentary, vertical, cross-sectional view through a pair of operating handles showing the primary shaft in elevation and illustrating two of the spring clutch assemblies.

Fig. 8 is a detailed, transverse, cross-sectional view taken on irregular line VIII—VIII of Fig. 7.

Fig. 9 is a cross-sectional view similar to Fig. 3, but extended to fragmentarily illustrate one of the merchandise sections in elevation and an ejector assembly in section.

Fig. 10 is a fragmentary, cross-sectional view taken on line X—X of Fig. 9.

Fig. 11 is a fragmentary, detailed, cross-sectional view taken on line XI—XI of Fig. 9; and

Fig. 12 is a cross-sectional view showing the captive link assembly in elevation.

While the vending machine hereof has been adapted particularly for the vending of packages of gum 10, it will be appreciated after a full understanding of the operation, that various other articles of merchandise may be vended through use of the novel arrangement about to be set forth.

The particular vending machine chosen for illustration has three separate assemblies, all operably connected in a manner to be subsequently outlined herein, but inasmuch as each is provided with a reciprocable ejector 12, the mechanical movement for one of such ejectors 12 will first be outlined.

The packages of gum 10 are disposed in side-by-side stacks 14 and 16, and held in such position by a pair of spaced-apart, vertical panels or walls 18 and 20, each having a pair of inturned, vertical flanges 22 which cooperate with a partition 23, setting off a pair of side-by-side stack-receiving compartments as shown in Fig. 10 of the drawings.

50 A U-shaped support member having a bottom or bight portion 24, is provided with a pair of upstanding legs 26 and 28 secured directly to the outermost faces of the panels 18 and 20 respectively, with the lowermost edges of the latter, as well as the lowermost edges of the flanges 22 and the partition 23 spaced above the bottom wall 24.

55 The rearmost leg 28 is secured directly to the innermost face of rear wall 30 forming a part of a hollow cabinet, broadly designated by the numeral 31, to which rear wall 30 is also attached the wall 18. One of the stacks 14 or 16 of articles 10 always rest upon the uppermost surface of bottom wall 24, whereas, the other stack rests upon the ejector 12.

Ejector 12 consists of an elongated bar having essentially the same dimensions as the packages 10, and is disposed upon the uppermost surface of wall 24 for transverse movement therealong within the confines of legs 26 and 28 and beneath the lowermost edges of panels 18 and 20, flanges 22 and partition 23. Wall 24 is provided with a transverse, elongated slot 32 disposed preferably midway between the legs 26 and 28 below partition 23 for clearing a vertical pin 34 secured to the ejector 12.

and depending therefrom. Pin 34 receives a cam plate 36 beneath the wall 24 through the medium of an elongated slot 38 formed in the latter, plate 36 supporting a collar 40 freely mounted on the pin 34 and extending upwardly into the slot 32. A pin 42 for pivotally mounting the cam plate 36, depends from the wall 24 between slot 32 and leg 26, and a small spacer 44 on the pin 42, is interposed between the lowermost face of wall 24 and the uppermost face of cam plate 36.

An L-shaped bracket having one leg 45 thereof secured to the wall 30 (see Fig. 1) and the other leg 46 thereof underlying the plate 36, extends forwardly beyond the leg 26, such extended portion of the leg 46 having a longitudinal slot 48 formed therein. The wall 24 is offset forwardly of the leg 26 and is provided with an extension 50 overlying leg 46 and provided with an elongated slot 51 aligned with the slot 48. Each of the two outermost extensions 50 of the three assemblies, has an L-shaped bracket 52 for journaling a shaft 54 that in turn receives a member 56 for swinging movement on shaft 54 which is itself rotatable in the bearing brackets 52. Member 56 is held biased in the position illustrated in Fig. 3 by means of a spring 58 interconnecting member 56 and an upward extension 59 on the leg 46. One end of member 56 extends through the aligned slots 48 and 51 for free sliding movement therein and through an opening 60 formed in an elongated link 62 adjacent one end of the latter, link 62 being loosely attached to the member 56 between the leg 46 and the extension 50.

A roller 64 is mounted on the uppermost face of link 62 adjacent the opposite end thereof. The cam plate 36 is provided with a substantially semi-circular slot broadly designated by the numeral 66 and disposed on that side of the pivot pin 42 opposite to the pivot pin 34. Slot 66 has a bight 68 and a pair of wing portions 70 and 72 that terminate at points 74 and 76 respectively in diametrically opposed relationship with respect to the pin 42. Additionally, the plate 36 is provided with a pair of spaced-apart, semi-circular notches 78 and 80 within the bight 68. The link 62 directly underlies the cam plate 36 and roller 64 extends upwardly into the slot 66.

As above indicated, there are three of such mechanisms for vending articles of merchandise 10, and as shown in Fig. 1 of the drawings, there are three separate vertical supports for such merchandise. Each of these three vertical supports has a partition 23 for separating two stacks of articles 10, both of which stacks are controlled by a single ejector 12. Shaft 54 extends along the front wall of the three legs 26, rearwardly of the extension 59 and above extension 50 as shown most clearly in Fig. 9 of the drawings.

A decorative cover plate 82 on the extension 59 extends into an access opening 84 for the vended merchandise 10, which opening 84 is formed in a hollow cover 86 that is hingedly secured to the rear wall 30 of case 31 as at 88. The cover plate 82 is provided with slots 90 for clearing handles 92 having finger pieces 94 thereon. There is a handle 92 swingably mounted on shaft 54 adjacent each member 56 respectively.

Special clutch means is provided for interconnecting the handles 92 and their corresponding members 56 which takes the form of a spring 96 coiled about the shaft 54 and best illustrated in Figs. 7 and 8 of the drawings. Each handle 92 is provided with a laterally extending ear 100, and each member 56 is likewise provided with a laterally extending ear 98, ears 98 and 100 being relatively overlapped as shown in Figs. 8 and 10.

Spring 96 has an end 102 in underlying engagement with the ears 98 and 100, and an end 104 in overlying engagement with the ears 98 and 100, ends 102 and 104 being biased toward each other and normally holding the ears 98 and 100 against separation. It is thus seen that when a finger piece 94 is depressed downwardly to swing the handle 92 downwardly in a slot 90, the interconnection between handle 92 and its member 56 provided

by spring 96, will cause the two elements 92 and 56 to swing together on the shaft 54. However, if the member 56 is restrained against swinging movement with the handle 92, ear 100 will move upwardly with respect to ear 98 and the end 104 will yield to move away from the end 102. Each member 56, which, like the handles 92, are swingable on the rotatable shaft 54, are also operably connected with shaft 54. A laterally extending lug 106 is rigidly secured to shaft 54 adjacent each member 56 respectively, and each lug 106 has a pin 108 thereon parallel with the shaft 54 and extending into an arcuate slot 110 formed in the member 56 above the shaft 54 concentric with the axis of rotation of the latter. Thus, when any one fingerpiece 94 is depressed to swing its handle 92 downwardly, and the corresponding member 56 is swung therewith on shaft 54 through the clutch connection 96, member 56 will also rotate shaft 54 by engaging a corresponding pin 108 and swinging the lugs 106.

10 A small latch member provided with a straight top portion 114 having a notch 116 therein, is pivotally mounted as at 118 on each member 56 respectively, directly above slot 110 thereof, there being a second notch 120 in the lowermost edge of the latch 112 cooperable with 15 the underlying pin 108 that extends through slot 110 beyond that face of member 56 opposite to lug 106. A bracket on extension 59 for each latch 112 respectively, has a depending ear 122 cooperable with notch 116 and disposed directly above the latch 112.

20 A single coin control apparatus 124 is provided for the three vending mechanisms and is releasably attached to the wall 30 by a latch 126. The apparatus 124 is for the most part, conventional in that the same is adapted to receive a coin inserted at the top thereof through a 25 slot not shown, in the cover 86 for unlocking the apparatus 124 and rendering one of the handles 92 depressible. The coin is either rejected automatically and returned to the potential customer through the access opening 84, or is accepted and falls within a collection 30 box 128. The apparatus 124 is swingably secured to the shaft 54 through the medium of a link 130 whereby apparatus 124 may be swung away from wall 30 after releasing latch 126, thereby rendering the removable coin box 128 accessible for emptying.

35 The apparatus 124 is also operably connected with the shaft 54 through the medium of a link 132, which is not only pivotally connected to a lug 134 rigidly attached to shaft 54 adjacent to end proximate to coin apparatus 24, but is pivotally connected to a ratchet plate 136 forming a part of the apparatus 124 and rotatable thereon by means of a pivot pin 138. As can be seen in Fig. 2, lug 134 may be conveniently shaped in a configuration similar to lugs 106 shown in Fig. 9. Ratchet plate 136 cooperates with a spring-loaded pawl 140 to present full-stroke mechanism in the usual manner.

40 Details of construction of apparatus 124 need not be set forth for it may be pointed out that the ratchet plate 136 may swing only a short distance in the direction of the arrow in Fig. 2 in absence of insertion of a coin, and therefore, the apparatus 124 remains normally locked and permits only limited downward swinging movement of handles 92. In Fig. 4 of the drawings, one of the handles 92 is shown depressed to the limit of its travel as permitted by ratchet 136 when the apparatus 124 is 45 in such locked condition. If such depressed handle 92 is released from the position shown in Fig. 4, a spring 142 will return the ratchet plate 136 to the normal position shown in Fig. 2, and spring 58 will return the corresponding member 56 to the normal position shown in Fig. 3 50 of the drawings.

45 Captive link mechanism broadly designated by the numeral 144 of conventional character, is provided to prevent the depressing of more than one handle 92 at a time. The captive link assembly 144 is located immediately below the leg 46 as is clear in Figs. 2 to 6 inclusive,

9 and 11, within the path of travel of the members 56 that extend downwardly below the leg 46. As is clear from Fig. 12, mechanism 144 conventionally includes a plurality of blocks 202 slidably confined within a casing 204 of dimensions exceeding the combined dimension of blocks 202 in the direction of sliding movement of the latter by an amount adapted to permit interpositioning of only one member 56 between an adjacent pair of blocks 202 or between a block 202 and casing 204. Blocks 202 are bevelled as at 206 for sliding movement thereof when a member 26 is forced theretoward.

Each ejector 12 is rendered operable after insertion of a coin only if the two chambers, one on each side of partition 23, has merchandise 10 therein. To this end there is provided a small trigger 146 beneath each wall 24 directly below the partition 23 as shown in Fig. 10, and pivotally mounted on a horizontal pin 148. In absence of stacks of merchandise 14 and 16, the trigger 146 is weight-biased to extend upwardly into the path of travel of the ejector 12 by means of opening 150 in the wall 24. The articles 10 are pushed from the wall 24 for gravitation to an arcuate guide 152 therebelow which directs the merchandise 10 toward the access opening 24.

The machine is loaded by opening of the cover 86 and by way of example, six stacks of articles 10 are formed to present three different types of merchandise which the customer may select upon insertion of a coin. Assuming that the lugs 106 are held in the position shown in Fig. 9 with pins 108 engaging one end of the slots 110 by the action of spring 142, and that all of the members 56 are held in the position shown in Figs. 3 and 9 of the drawings, and assuming further, that roller 64 is within notch 80 as shown in Fig. 10 of the drawings, a coin is inserted and received by the apparatus 124, unlocking the ratchet plate 136 for complete rotation. The nature of the merchandise may be marked on the fingerpieces 94 and the customer may make his selection. As soon as one of the handles 92 is depressed, link 62 will be actuated to shift the roller 64 into the wing 72 until roller 64 engages the cam plate 36 at terminus point 76. Continued movement of member 56 toward the innermost end of slots 48 and 51 will cause the cam plate 36 to swing on pivot point 42 from the position shown by Fig. 10 to the position illustrated in Fig. 11 of the drawings. Such movement of the plate 36 shifts the pin 34 to that end of the slot 32 disposed beneath the stack 14 of articles 10 carrying therewith the elongated ejector bar 12 for sliding movement along the bottom wall 12 transversely thereof. Ejector bar 12 moves from beneath the stack 16 of articles 10, against the lowermost article 10 of stack 14 thereof, moving such lowermost article from the wall 24 to the arcuate guide 152 and the vending station accessible by opening 84.

When the ejector bar 12 clears the stack of merchandise 16, such stack 16 gravitates to a position where the lowermost package 10 thereof rests upon the wall 24 and upon the trigger 146, alongside the ejector 12. Such lowermost article 10 of the stack 16 is thereupon ready for vending during the next cycle of operation of the vending machine if the next customer makes the next selection. When member 56 is released, spring 58 operates to return the same to the normal position shown in Figs. 3 and 9, carrying therewith the link 62. Roller 64 will move within the wing portion 72 away from the terminus point 76 and come to rest within the notch 78. During the next cycle of operation of the particular vending mechanism, actuation of member 56 will shift the link 62, moving roller 64 into the wing 70 until roller 64 engages terminus point 74.

Continued movement of the member 56 will swing the plate 36 in the opposite direction from the position shown in Fig. 11 to the position illustrated by Fig. 10. Ejector bar 12 will move from beneath stack 14 to a position supporting stack 16 and the roller 64 will ultimately come to

rest within the notch 80 as shown in Fig. 10 of the drawings.

It is seen from the foregoing that swinging movement of member 56 on the axis 54, is transmitted into swinging movement or oscillatory action on the part of cam plate 36 and into reciprocable movement on the part of ejector 12 along a path of travel that is substantially parallel with the axis of swinging movement of member 56.

When any one handle 92 is shifted from the position shown in Fig. 3, to the positions of Figs. 4, 5 or 6, member 56 will immediately shift the blocks 202 of captive link assembly 144 to prevent swinging movement of the remaining members 56, and accordingly the remaining handles 92, away from the normal position of Fig. 3.

After insertion of a coin in the apparatus 124 to unlock the same for swinging movement beyond the position shown in Fig. 4, such coin will drop into the coin box 128 when the arm 92 reaches the position shown in Fig. 5. At this point the latch member 112 operates to prevent upward swinging movement of the handle 92, back to the position shown in Fig. 3 by engaging the pin 108 within the notch 120, it being understood that retrograde movement of the shaft 54 is prevented by the full-stroke mechanism that includes pawl 140 and plate 136. Latch 112 does not however, prevent continued movement of arm 92 to the full end of its stroke as shown in Fig. 6, and, after vending of an article 10, return of the arm 92 to the position shown in Fig. 3, will cause the latch 112 to assume the position shown in Fig. 3 by virtue of ear 122 engaging in notch 116. Thus, it is impossible for the machine to become locked so that the customer cannot receive the merchandise which he selected once his coin has been accepted and deposited in the coin box 128. Also, it is impossible for a customer to select more than one article since only one handle 92 can be actuated at a time.

Having thus described the invention what is claimed as new and desired to be secured by Letters Patent is:

1. For use in a vending machine of the type delivering successive articles from a vertical stack by horizontal reciprocation of delivery mechanism and including coin operable apparatus having normally locked structure releasable for movement upon insertion of a coin, manually operated actuating means for said mechanism comprising a single, rotatable, horizontal shaft pivotally mounted in the machine and adapted to be connected to said structure; an elongated, operating-handle element provided at one end with a laterally extending ear and at the other end with a manually manipulable finger piece, said element being pivotally mounted intermediate its ends on said shaft for free swinging movement thereon thereby permitting vertical swinging movement of said finger piece through predetermined, acute arcs above and below the horizontal plane of the shaft and to one side of the latter; an elongated mechanism actuating member provided at one end thereof with an elongated extension adapted for engagement with said mechanism, said member having a laterally extending ear thereon and being pivotally mounted intermediate its ends on said shaft for free swinging movement thereon in spaced relationship to said element thereby permitting swinging movement of said extension through predetermined, acute arcs to either side of the vertical plane of the shaft and below the latter, the ear of the member extending toward said element and being normally overlapped with the ear of the element; a coil spring disposed about the shaft between the element and the member, said spring being tensioned and having one end in overlying engagement with the ear of the element and an opposite end in underlying engagement with the ear of the member for biasing said ears toward their normal, overlapped position; an upstanding lug rigidly mounted on the shaft and extending radially therefrom adjacent the member; means for interconnecting the lug and the

member when the latter is swung in one direction, the member being normally swingable with respect to the lug in the opposite direction; and a latch pivotally mounted on said member and movable into engagement with the upstanding lug on the shaft for preventing swinging movement of the member relative to said lug when the member is swung in said opposite direction thereby completely interlocking the lug and the member against relative rotation.

2. For use in a vending machine of the type delivering successive articles from a vertical stack by horizontal reciprocation of delivery mechanism and including coin operable apparatus having normally locked structure releasable for movement upon insertion of a coin, manually operated actuating means for said mechanism comprising a single, rotatable, horizontal shaft pivotally mounted in the machine and adapted to be connected to said structure; an elongated, operating handle element provided at one end with a laterally extending ear and at the other end with a manually manipulable finger piece, said element being pivotally mounted intermediate its ends on said shaft for free swinging movement thereon thereby permitting vertical swinging movement of said finger piece through predetermined, acute arcs above and below the horizontal plane of the shaft and to one side of the latter; an elongated, mechanism-actuating member provided adjacent its uppermost end with an arcuate slot, adjacent its lowermost end with a longitudinal extension and intermediate its ends with a laterally extending ear, said member being pivotally mounted intermediate its ends on said shaft for free swinging movement thereon in spaced relationship to said element

5

thereby permitting swinging movement of said extension through predetermined, acute arcs, to either side of the vertical plane of the shaft and below the latter, the ear of the member extending toward said element and being normally overlapped with the ear of the element; a coil spring disposed about the shaft between the element and the member, said spring being tensioned and having one end in overlying engagement with the ear of the member for biasing said ears toward their normal overlapped position; an upstanding lug rigidly mounted on the shaft and extending radially therefrom adjacent the uppermost end of the member, there being a pin on the lug and extending laterally from the latter in parallelism with the shaft, said pin extending through said slot in the member for limiting swinging movement of the member relative to the shaft; and a latch pivotally mounted on said member adjacent the uppermost end of the latter and movable into engagement with the pin on the upstanding lug for further limiting swinging movement of the member relative to the shaft in one direction when the member has been swung in the opposite direction.
